UNITED STATES PATENT OFFICE.

JOHN L. BENNETT, OF DECATUR, ILLINOIS, ASSIGNOR TO UNITED STATES WIRE MAT COMPANY, OF DECATUR, ILLINOIS, A CORPORATION OF ILLINOIS.

IMPLEMENT OR DEVICE FOR KILLING OR DISABLING INSECTS, FLIES, OR THE LIKE.

1,218,619.

Specification of Letters Patent.

Patented Mar. 13, 1917.

Application filed September 7, 1915. Serial No. 49,192.

To all whom it may concern:

Be it known that I, JOHN L. BENNETT, a citizen of the United States, a resident of Decatur, in the county of Macon and State 5 of Illinois, have invented certain new and useful Improvements in Implements or Devices for Killing or Disabling Insects, Flies, or the like, of which the following is a specification.

10 This invention relates to improvements in implements or devices for killing or disabling insects, flies or the like, by striking, and the principal object is the provision of such a device which is simple and strong in 15 construction and attractive in appearance and capable of withstanding extended use.

Another object of this invention is the provision of such a device which is strongly made and braced so as to give requisite 20 flexibility without weakening the same and so as to prevent cupping of the body portion.

A further object is the provision of such 25 a device which has its side edges folded over to provide edge portions of three-ply thickness and having its end edge covered with a flexible binding or covering, the ends of which are folded in with the side edges, whereby a strong, satisfactory, durable and 30 symmetrical article is provided.

To the accomplishment of the foregoing and such other objects as may hereinafter appear, my invention consists in the construction, combination and arrangement of 35 parts hereinafter described and then sought to be defined in the claims, reference being made to the accompanying drawings forming a part hereof, it being understood that this showing is made merely for the purpose 40 of illustrative disclosure and that various changes may be made in practice within the scope of the claims without digressing from my inventive idea.

In the drawings,

45 Figure 1 represents a rear elevation of a device constructed according to my invention.

Fig. 2 is an enlarged view of a part of the top edge, the binding being broken away to 50 show the selvage.

Fig. 3 is a perspective view of one of the top corner portions taken on an enlarged scale, showing the manner of folding the side edges and binding.

55 Fig. 4 is a horizontal section through one

side of the body of the device showing the manner of folding the side edges.

In practice, it is found desirable to have a killer with its top or outer end covered by a binding to prevent injury to the surface 60 which is struck and also one which is reinforced and braced so as to withstand the severe use to which an article of this character is subjected. It is also very advantageous to provide a construction whereby 65 the binding is prevented from pulling off particularly at its ends. Simplicity and symmetry in appearance are also desirable, particularly from a selling standpoint. To meet these requirements, I have designed the 70 article disclosed in this application.

Referring now to the drawing, the numeral 1 designates the body portion of the killer, this being preferably constructed of reticulated metallic material, such as woven 75 wire netting or the like. This body portion is substantially rectangular in shape, the top edge 2 being a selvage edge and the side edge portions 3 being folded over a plurality of times, providing a portion of at 80 least three-ply thickness. The lower corners of the body portion are folded along lines 4 which converge to a point, whereby a substantial portion of three-ply thickness 5 is provided. The handle 6 is bifurcated to receive 85 this portion of the body of the device, the stay plate 7 being positioned in front and the parts being connected by securing means 8, preferably rivets. It is to be noted that the upper bearing edge of the stay 90 plate is located adjacent the intersection of the folding lines of the lower corners of the body portion.

To the outer or top selvage 2 I attach the binding or covering of flexible material 9 95 by means of the row of stitching 10 through a row of meshes removed from the edge. The binding material is in the form of a sheet folded over the top edge of the body portion and extends downwardly on each 100 side thereof so as to cover several meshes. This prevents the binding or covering pulling out. This binding or covering is applied before the side edges are folded and when this latter operation takes place, the 105 said binding or covering 9 will be similarly folded as at 11, and subjected to considerable pressure so that the parts will remain in their folded position.

The folding of the edge portions provides 110

a strong and simple reinforcing means and the folding of the lower corners provides obliquely extended braces or trusses from the handle to the edge. The binding or covering 9 is securely held by means of the stitching, folding and pressing.

It is therefore seen that I have provided an article which is strong in construction, attractive and symmetrical in appearance and efficient in operation. The construction is strengthened where necessary to give the most wear, thus making a killer which is exceedingly durable. The various improvements in details of construction render this article a material improvement in the art.

What I claim is,—

1. A device of the character described including a handle portion and a body portion, said body portion being composed of wire netting and having its side edges folded over to provide reinforced edge portions, a binding for the top edge secured to the body portion and having its ends folded within the folds of the side edges.

2. A device of the character described in-

cluding a substantially rectangular body portion and a handle portion, the side edge portion being folded over a plurality of times to provide edge reinforcements, the lower corners of said body portion being folded over said body portion and each other so that the edges thereof extend obliquely whereby the obliquely extending portions of the edges provide stays or braces for the body portion in flexing, a binding for the top edge having its ends folded in with said side edges.

3. A device of the character described including a handle portion and a body portion, said body portion being composed of wire netting and having its side edges folded over a plurality of times to provide reinforced edge portions, a binding for the top edge secured to the body portion by stitching through meshes removed from the end meshes and having its ends folded within the folds of the side edges, the folded end portions of the top edge of the body and the binding being pressed together.

JOHN L. BENNETT
